Charles H. Kestenman, Providence, R. I., assignor
to Kestenman Bros. Mfg. Co., Providence, R. I., a corporation of Rhode Island

Application December 30, 1937, Serial No. 73,977

Term of patent 7 years

To all whom it may concern:

Be it known that I, Charles H. Kestenman, a citizen of the United States, residing in the city of Providence, county of Providence, and State of Rhode Island, have invented a new, original, and ornamental Design for a Bracelet Chain or the like, of which the following is a specification, reference being had to the accompanying drawing, forming a part thereof, in which:

Fig. 1 is a perspective view of the bracelet chain or the like illustrating my new design;

Fig. 2 is a plan view of the bracelet chain or the like; and

Fig. 3 is an edge view of the same.

I claim:

The ornamental design for a bracelet chain or the like, substantially as shown.

CHARLES H. KESTENMAN.
